His Attorney

UNITED STATES PATENT OFFICE.

EDGAR D. DICKINSON, OF SCHENECTADY, NEW YORK, ASSIGNOR TO GENERAL ELECTRIC COMPANY, A CORPORATION OF NEW YORK.

SHIP PROPULSION.

1,269,404.

Specification of Letters Patent. Patented June 11, 1918.

Application filed November 3, 1917. Serial No. 200,026.

To all whom it may concern:

Be it known that I EDGAR D. DICKINSON, a subject of the King of Gt. Britain, residing at Schenectady, in the county of Schenectady, State of New York, have invented certain new and useful Improvements in Ship Propulsion, of which the following is a specification.

The present invention relates to ship propulsion, and has for its object to provide an improved system for use on vessels which are required to be driven at different times at widely different speeds. Such a condition is met with, for example, in war vessels which for the greater part of the time are operated at cruising speed, but at times are required to operate at higher or maximum speeds.

For a consideration of what I believe to be novel and my invention, attention is directed to the accompanying specification and the claims appended thereto.

In the drawing, the figure is a diagrammatic plan view of an installation embodying my invention.

Referring to the drawing, 1 indicates a propeller shaft, 2 a propeller, and 3 a gear wheel on the propeller shaft through which the shaft is driven. Meshing with the gear wheel 3 are two driving pinions 4 and 5 mounted on shafts 6 and 7. Connected to the shaft 6 is a high pressure turbine 8 and a cruising turbine 9, and connected to the shaft 7 is a low pressure turbine 10. Elastic fluid is conveyed to the turbine 8 by a conduit 11 provided with a suitable valve 12. A conduit 13 is also provided through which elastic fluid may be admitted directly to an intermediate stage of the turbine, thus bypassing the first stages. The purpose of this, as is well understood, is to enable the machine to take more elastic fluid thus increasing its power. In conduit 13 is a suitable valve 14. Elastic fluid is admitted to the cruising turbine 9 by a conduit 15 in which is a regulating valve 16. The exhaust end of the cruising turbine 9 is connected by a conduit 17 to the admission end of the high pressure turbine 8 so that these two turbines may be connected in series. In conduit 17 is a valve 18. The exhaust end of high pressure turbine 8 is connected by a conduit 19 to the admission end of low pressure turbine 10. Leading from the casing of low pressure turbine 10 is an exhaust

conduit 20 which connects with a suitable condenser (not shown) in the well known manner. Extending across the casing of the cruising turbine 9 is a diaphragm 21 which forms a chamber 22 in which is a 60 reversing turbine element or wheel 23 to which elastic fluid may be fed by a conduit 24 provided with a suitable valve 25. Leading from chamber 22 is a conduit 26 which conveys the exhaust from the reversing element 23 to a reversing element 27 located in the exhaust end of the casing of low pressure turbine 10. The elements 23 and 27 thus bear the relation to each other of high pressure and low pressure reversing 70 elements respectively. 28 is a conduit leading from the cruising turbine casing to the condenser by means of which such casing can be connected to the condenser. In conduit 28 is a valve 29. 75

For cruising operation the valves 12, 14, 25 and 29 are closed and the valves 16 and 18 are open. Elastic fluid then flows from conduit 15 through cruising turbine 9, conduit 17, high pressure turbine 8, conduit 19, and low pressure turbine 10 to the exhaust conduit 20, and thence to the condenser. The three turbines are thus connected in series and drive the propeller shaft in the forward direction through the 85 two pinions 4 and 5 and gear wheel 3.

For higher speed operation the valves 14, 16, 18 and 25 are closed and the valves 12 and 29 are opened. This then admits elastic fluid directly to the high pressure turbine 8 90 from which it flows through the low pressure turbine 10 to the condenser, the two turbines thus operating in series. Since the valve 29 is open, the casing of the cruising turbine is connected to the condenser, and 95 hence its rotor runs idle in a vacuum equal to that of the condenser. The losses, therefore, due to the cruising turbine running idle are low.

For the highest speed, the valve 14 is 100 opened to admit elastic fluid to an intermediate stage of the high pressure turbine 8, thus by-passing the earlier stages, the valves 12 and 29 being also open and valves 16, 18 and 25 closed. 105

Under all the conditions of forward operation, as referred to above, it will be noted that the reversing elements 23 and 27 run in vacuum and that they are inherently connected to vacuum due to the turbine ar- 110

arrangement, since the element 27 is located in the exhaust end of the low pressure turbine 10, and the chamber 22 in which element 23 is located is connected to such exhaust and 5 by conduit 26. This is a most advantageous arrangement as it requires no special piping or valves to connect the chambers in which the reversing elements run to the condenser when they are running idle.

10 For reverse operation the elastic fluid admission valves 12, 14 and 16 are closed and the valve 25 is opened. Elastic fluid then flows through the high pressure reversing element 23 and thence by way of conduit 26 15 to the low pressure reversing element 27 from which it passes to the exhaust conduit 20.

In ship propulsion installations of this character it is usually desirable in practice 20 to provide suitable steam connections so that in case of emergency any of the turbines may be run independently of the others and as is obvious such connections may be readily provided in connection with the present 25 system.

The arrangement shown is for a single propeller and it will be understood that for any ship having more than one propeller it will be duplicated for the other propeller or 30 propellers.

In accordance with the provisions of the patent statutes, I have described the principle of operation of my invention, together with the apparatus which I now consider to 35 represent the best embodiment thereof; but I desire to have it understood that the apparatus shown is only illustrative and that the invention can be carried out by other means.

40 What I claim as new and desire to secure by Letters Patent of the United States, is:

1. In a ship propulsion system, the combination of a propeller, two shafts arranged in parallel for driving the propeller, a high 45 pressure turbine and a cruising turbine on one of said shafts, a low pressure turbine on the other, means for connecting said turbines in series for cruising speed, and the high pressure and low pressure turbines in

series for higher speeds, reversing turbine elements in the low pressure ends of the 50 cruising turbine and low pressure turbine casings, and means for supplying elastic fluid to them in series.

2. In a ship propulsion system, the combination of a propeller, a propeller shaft, a gear wheel on the shaft, two driving shafts each of which has a pinion meshing with 55 said gear wheel, a high pressure turbine and a cruising turbine on one of said driving 60 shafts, a low pressure turbine on the other, means for connecting all these turbines in series, or the high pressure and the low pressure turbines in series, and means for connecting the casing of the cruising turbine 65 to a region of low pressure.

3. In a ship propulsion system, the combination of a propeller, a propeller shaft, a gear wheel on the shaft, two driving shafts each of which has a pinion meshing with 70 said gear wheel, a high pressure turbine and a cruising turbine on one of said driving shafts, a low pressure turbine on the other, means for connecting all these turbines in 75 series, or the high pressure turbine and the low pressure turbine in series, a reversing element associated with each driving shaft, and means for connecting them in series.

4. In a ship propulsion system, the combination of a propeller, a propeller shaft, a gear wheel on the shaft, two driving shafts each of which has a pinion meshing with 80 said gear wheel, a high pressure turbine and a cruising turbine on one of said driving shafts, a low pressure turbine on the other, 85 means for connecting all these turbines in series, or the high pressure turbine and the low pressure turbine in series, a high pressure reversing element in the low pressure end of the cruising turbine casing, a low 90 pressure reversing element in the low pressure end of the casing of the low pressure turbine, and means for supplying elastic fluid to said reversing elements in series.

In witness whereof, I have hereunto set 95 my hand, this 1st day of November, 1917.

EDGAR D. DICKINSON.
